UNITED STATES PATENT OFFICE.

ERNEST C. MIGNON, OF ELMIRA, NEW YORK

WIRELESS SIGNAL-RECEIVING APPARATUS.

1,329,672.

Specification of Letters Patent.

Patented Feb. 3, 1920.

Application filed November 29, 1916. Serial No. 134,121.

To all whom it may concern:

Be it known that I, ERNEST C. MIGNON, a citizen of the United States, residing at Elmira, in the county of Chemung and State of New York, have invented certain new and useful Improvements in Wireless Signal-Receiving Apparatus, of which the following is a specification.

This invention has relation to the wireless transmission of radiant energy, and particularly to the reception of the same in the form of telegraph, or telephone signals.

One of the objects of the invention is to provide a system of this character embodying all of the necessary and essential signal receiving elements, arranged in proper conformity to each other, and constituting a compact unit of efficiency, that has heretofore been obtainable only by the use of a number of connected, but spaced instruments, to prevent mutual interference through induction.

Another object of the invention is to provide a receiving system embodying the audion type of detector and a novel arrangement of associated inductance and capacity elements, for permitting the production of "beat" oscillations whereby sustained or undamped waves may be received.

Another object of the invention is to provide in a system of the character above set forth, an arrangement of inductances, providing practicably non-leaking magnetic fields and enabling the transformation of a maximum amount of energy; said arrangement acting to reduce the sensitivity of the system to variations in the frequency of the oscillations due to the close proximity of objects or the operator's body.

Another object of the invention is to provide a novel and easy manipulatable means associated with the inductance elements of the system whereby the magnetic fields thereof may be interlinked to permit variations of inductance between the elements for the purpose of tuning, altering the frequency of oscillations in the audion circuit or the like, thereby permitting the inductances to remain in permanent fixed relation.

Another object of the invention is to provide in an audion receiving system an electric coil means for association with the audion to influence the operation of the same

whereby the incoming oscillations passing therethrough may be synchronized with the local oscillations to clarify the signals and to generally improve the manifestation thereof.

Another object of the invention is to provide a cabinet in which all the necessary elements are compactly arranged and contained therein with a panel provided with dials, knobs, switches, etc., operatively associated with the working parts within the cabinet whereby manipulation and relative adjustment of the elements may be quickly and accurately obtained from without the cabinet.

In addition to the foregoing this invention comprehends improvements in the details of construction and arrangement of parts to be hereinafter set forth and particularly pointed out in the appended claims.

The above and additional objects are accomplished by such means as are illustrated in their preferred embodiment and in the accompanying drawings, wherein like characters of reference denote like or corresponding parts throughout the several views in which:—

Figure 1 is a perspective view of the complete device constructed in accordance with my invention.

Fig. 2 is a vertical longitudinal section through the cabinet looking toward the rear of the operating mechanism.

Fig. 3 is a section on the line 3—3 of Fig. 2.

Fig. 4 is a diagrammatic view showing the "hook-up" of the various parts of the apparatus.

Fig. 5 is a view showing the "hook-up" of the various parts of the apparatus, in a much simpler diagram than Fig. 4 to facilitate an easier understanding of the invention.

The cabinet 1 is of a depth sufficient to conveniently receive all the elements of the apparatus which may be arranged upon and attached to the rear side of a front panel 2 of suitable insulating material. Arranged adjacent the lower edge of the panel is a pair of binding posts 3 and 4, the post 3 receiving the connecting wire from the aerial antennæ as indicated by the character A inscribed on the panel. The ground wire is fastened to the binding post 4, this post also being designated by the character G on the

panel 2. The aerial circuit *a*, included in the "hook-up", has its terminals connected to the binding posts 3 and 4, and, referring to Fig. 4 of the drawing, it will be seen that the aerial post 3 is in circuit with one of the eleven terminals of the primary switch 5.

Three flat coils, 6, 7 and 8 are arranged clover-fashion at the rear of the panel and the relative position of these coils is significant and is an important feature of the proper operation of the apparatus. These coils, one primary and two secondary, are mounted upon supporting studs 9 carried by the panel 2 and each stud is of a length sufficient to hold the corresponding coil in spaced relation to the panel 2 as shown by Fig. 3 of the drawing. Ten windings are provided in each coil, thereby making eleven terminals, and each terminal of the windings is "hooked-up" to the corresponding switch, the terminals in the winding of the primary coil 6 being wired to the primary switch 5, while the terminals in the windings of the secondary coils 7 and 8 are wired to the two secondary switches 10 and 11 respectively.

It is to be noted that the relative triangular position of the coils, 6, 7 and 8, having their peripheries in engagement and all lying in the same plane provides a central space 12 between the coils, the center of which is equidistant from the center of each coil. Extending through the space 12 is a rotatable shaft 13 which has one end rotatably mounted in a bushing 14 carried by the panel 2. Beyond the bushing 14 the shaft has a knob 15 by which the shaft may be rotated. A triangular supporting plate 16 of insulating material is carried by the studs 9 and assists in supporting the coils 6, 7 and 8. A bushing 17 in the center of the plate 16 receives the shaft 13—the two bushings 14 and 17 thereby providing bearings for permitting the rotation of the shaft and also longitudinal sliding movement thereof in the bearings. The shaft is extended beyond the bushing 17 and its end is normally disposed considerably beyond the coils 6, 7 and 8 as shown in Fig. 3. Secured to this end of the shaft is what may be termed an adjustable core 18 in the form of a metallic ring 19 having an ear 20 which is fastened to the said shaft 13. Extending diametrically opposite the ring is a balancing member 21 which is approximately equal in weight to the ring 19. The free end of the balancing member 21 carries a set screw 22 which may be longitudinally adjusted for obtaining a perfect balance between the balancing member 21 and the ring 19. The ring 19 is constructed from any suitable metal, preferably soft iron, and may consist of a metal plate. The rotatable and longitudinally adjustable shaft permits the ring to be rotated so that its relative position with respect to the coils may be changed to

an unlimited degree. Being longitudinally movable, the shaft may be moved through the medium of the knob 15 for moving the ring or disk-core toward or away from the coils as shown by dotted lines in Fig. 3.

70

Referring now to the aerial circuit *a*, it will be observed, that when the switch lever 5' of the primary switch 5 is in engagement with one of the switch terminals, the circuit is completed through the corresponding 75 number of windings in the primary coil 6, through the switch lever 5' to the two primary binding posts 23 which are spaced apart and normally connected by a short wire 24. Adjacent the two primary posts 23 are two secondary posts 25, connected by a second short wire 26 and the purpose of these four posts will be hereinafter more fully referred to. From these primary posts 23 the aerial circuit *a* continues to the 80 ground terminal 4 thus completing the circuit. Shunted across the "aerial" and "ground", by virtue of its connection with the aerial circuit *a*, is a forty-three plate rotary variable condenser 27. This condenser 90 is adjusted by a knob 28 on the front of the panel 2 having a lever coöperating with a dial of 180 degrees whereby the area included between the plates of the condenser 27 may be properly varied when adjusting 95 the condenser.

90

I prefer to employ the audion type of detector in the present invention and especially the tubular form which is disposed in an upright position upon the front panel 100 of the cabinet and preferably at the left hand side as illustrated in Fig. 1. To increase the operative efficiency of the receiving system of the present invention I associate with the audion detector a magnetic coil device supported by a fiber tube 105 29 of a diameter preferably equal to its length as shown by Fig. 1 of the drawing. Adjacent the top of the fiber tube is a coil 30 consisting of a plurality of turns of magnet wire, the terminals of which are connected to the contact pins 31 and 32. At the lower end of the fiber tube is another coil 33, identical in construction with the coil 30, and which has its terminals connected to the contact pins 34 and 35.

105

The tube 29 and coils 30 and 33 circumscribe the audion detector 36 and within the bulb 37 are the usual grid 38 and wing 39. The filaments 40 are within the bulb as 120 clearly shown in the diagram of the "hook-up" in Fig. 4. One filament, however, has a free end extending into the atmosphere so that if the other filament breaks from its conductor, said filament with the free end 125 may be joined to said conductor.

110

The grid 38 is connected by means of its terminal to a binding post indicated at H, this character being inscribed upon the panel adjacent thereto to identify the same 130

and in the same manner a binding post for the wing 39 and two posts for the filament are disposed in proximity to the detector and identified by characters which indicate the circuit in which the posts are included. The binding post H is permanently placed in communication with a variable condenser 41 through the agency of a conductor 38^a and this condenser is a duplicate in construction and capacity to the aforescribed condenser 27 and is likewise adjusted by means of a knob 41^a upon the front of the panel. The opposite terminal of the condenser 41 is connected by means of a lead 42 to the contact arm 10' of the previously described switch 10 and an extreme contact pole of said switch is in electrical communication with the uppermost binding posts of the series 25 by means of a conductor 43. A pair of binding posts 44 and 45 are located upon the front of the panel and are adapted for connection to the negative and positive terminals respectively of a battery which is not, commercially, to form a part of the cabinet. The battery is, however, indicated in dotted lines at 46 in the diagram and the binding post 45 is connected by means of a lead 47 to the lowermost binding post of the series 25. A conductor 48 extends from the binding post 44 to the lowermost binding post F and as the same is directly connected by a conductor 49 to one filament terminal, the grid circuit is thus completed.

The binding post W adjacent the audion detector and to which the wing is connected is placed in communication by means of a conductor 50 with one of a pair of binding posts 51 and 52 upon the panel and to which the terminals of the phones 53 are to be connected, the post 52 being connected by means of a lead 54 with the pin 34 which in turn is connected to one terminal of the lower coil 33.

To energize the wing circuit I provide a battery 55 comprising twelve three-cell flashlight battery units, controlled by the nine terminal switch 56, the lever 57 traveling on a perfectly smooth surface formed by an arcuate strip of fiber 58 through which the terminals 59 project. The high tension battery 55 is in series with one of the terminals of the switch 11 which connects the secondary coil 8 by means of a lead 55^a while the lever 11' of this switch is connected to the lowermost one of the secondary posts 25. The mutual co-operation of the two secondary coils is established by the short wire 26 connecting the two secondary posts 25 and the wire 43 which joins these posts with the terminal of the first winding in the secondary coil 7. Therefore, by connecting the contact arm 57 of the high tension battery switch with the pin 35 of the lower auto transformer by means of a lead

coil 60 the wing circuit is established. The arm 57 may be adjusted by means of a knob 57^a upon the panel.

The filament circuit includes the filament battery 46, shown in the diagram in dotted lines and which may consist of 3 or 4 cells. An arm 61 of a rheostat 62 is connected by means of a lead 63 with the positive terminal 45 of the filament battery and the coils of the rheostat are connected to the contact pin 31 of the upper auto transformer winding 30 by means of a lead 63. The opposite terminal of this winding or coil 30 is joined with the heretofore unmentioned terminal of the filament 40. The opposite end of the filament is in circuit with the negative terminal 44 of the filament battery thus completing the filament circuit. For an obvious purpose I prefer to connect a choke coil 64 across the terminal 55^a of the battery 55 and the arm 57.

A third condenser similar in construction and capacity to condensers 27 and 41 may be provided at 65 with one terminal connected to the arm 10' of the switch 10 by means of a conductor 66 and the other terminal to the pin binding post 35 of the lower auto transformer coil by means of a conductor 67.

Thus it will be seen, that each element of the system having a movable or adjustable part is operable from without the cabinet by means of a knob, arranged in proper mutual proximity to permit the hand of the operator to travel from one knob to another, to quickly arrive at a proper adjustment to correctly and clearly receive a signal.

A much simpler diagram than Fig. 4 is shown in Fig. 5 to enable an easier understanding of the invention to be had. In Fig. 5, reference characters have been applied only to the main parts of the apparatus to avoid confusion.

In operation, incoming oscillations are received in the aerial circuit which includes the primary coil 6 and are induced by said coil into the secondary coil 7 which is included in the grid circuit. When the contact arm 10' is engaged upon any one of the contacts of the switch 10, a circuit is established from the coil 7 through said contact, through the conductors 43, 47 and 48 to the filament 40 of the detector and from thence to the grid 38, through the conductor 38^a to the condenser 41 and back to the coil 10 through the arm 10'.

During operation of the system, the filament 40 is heated by current from the battery 46 which enters the binding post 44 and passes through the conductor 48 to the filament. The circuit from the filament is then completed through the coil 30 through the conductor 63 to the rheostat coils 62, and from thence through the arm 61 thereof and conductor 63 back to the battery.

The wing circuit is energized by the current from the high tension battery 55, the voltage being regulated by contact of the arm 57 with any one of the contacts 59 whereby any number of cells may be included in series. The current is led from the said arm 57 through the lead 60 to the coil 33 and thence through the conductor 54 to the phones 53. The current leaves said phones 10 at the binding post 51 and traverses the lead 50 to the wing 39 of the detector from whence it crosses the gap within the bulb and impinges upon the heated filament. The said filament conducts the current 15 through the leads 49 and 48 to the lead 47 by way of the binding post 44 as a matter of convenience. From the lowermost binding post of the series 25, the current is led through as many of the coils of the wing 20 circuit inductance 8 as are included by engagement of the arm 11' with any one of the contacts of the switch 11. The conductor 55^a then completes the circuit through the battery 55.

25 The heating of the electrodes within the bulb 37, heats the gaseous body between these electrodes within the evacuated bulb and thus renders the molecules of such body active, in which condition the body is highly 30 sensitive to electrical oscillations. This body, I have found is still more sensitive when influenced by one or more coils, preferably magnetic, like 30 and 33.

From the foregoing it will be apparent 35 that a steady flow of negative electricity traverses the space between the wing and the filament of the detector, and in a well known manner the passage of a current, rectified from the induced oscillation in the 40 grid circuit, from the filament to the cold grid, interrupts the passage of the current in the wing circuit through the bulb whereby such interruptions are manifested by 45 audible signals in the phones.

50 For the reception of undamped waves the capacities 27 and 41 are adjusted, as well as the ring 18, by means of the knob 15 to vary the mutual inductance of the primary and secondary coils 6 and 7 until the detector acts as a generator to set up 55 local oscillations in the wing circuit. By still further varying the adjustment of the inductances and the capacities, the relative periodicity of the incoming and the local oscillations may be adjusted so as to create a difference of relative frequency which will be manifested in the nature of audible tones in the phones, of a rate of vibrations equal to the difference in frequency of the incoming 60 and local oscillations. By adjusting the ring 18 through a combination of its two movements, the difference of frequency between the two sets of oscillations may be varied to obtain the most desirable quality of 65 signal in the phones. And to further clarify

the signal the contact arm 11' may be moved from one contact to another of the switch 11 until the proper number of coils in the inductance 8 are included in the wing circuit.

In general use and under ordinary conditions it will be found sufficient to adjust the ring 18 to include the two secondary coils as shown by dotted lines in the diagram Fig. 4, whereby the induction between the primary 6 and the secondary 7 will take 70 place without the assistance of the ring. It is to be noted in this connection that owing to the formation of the inductances in flat coils and the relative disposition thereof in the same plane, the mutual inductance between the coils is considerably reduced and, therefore, when receiving undamped waves, the presence of the operator's body in proximity to the coils will not affect the relative 75 frequency of the oscillations within the circuit to cause annoying changes of pitch in the tone of the audible signals. This is a disagreeable feature of receiving undamped waves with a loose coupler. I desire to call 80 particular attention to the flat formation of the coils and their relative relation in the same plane with their edges adjacent, as the decrease of mutual inductance is due to this arrangement, and a primary and secondary coil may be operatively associated in this 85 manner without the necessity of a magnetic conductor such as the ring 18.

It will be apparent that this "hook-up," 90 with the windings of the coils 30 and 33, being opposite, one in series with the high tension battery 55 and the other in series with the filament battery 46, interference in the magnetic fields by induction is avoided during the absence of incoming signals. The incoming signal, however, will cause the 95 coils 30 and 33 to immediately become active whereby the impulses will be of uniform frequency and a strong stimulating effect imparted thereto. The effect of the magnetic fields is generally to urge the incoming 100 or oscillations passing through the bulb to synchronize with the local oscillations as the gaseous body within the evacuated bulb 105 37 is highly sensitized by the coils 30 and 33, so that the audible signals will be more apparent and clarified.

To receive damped waves from a spark station, it is only necessary to disconnect the wire 26 from the binding posts 25 and connect said posts to a loose coupler, loading coil or any suitable apparatus that may be necessary to tune the receiving apparatus to the wave length of the sending station, whereupon, the detector may be utilized to receive damped waves. The capacities, in 110 this case, are properly adjusted so that the grid circuit may be tuned to resonance with 115 regard to the wave length of the sending station.

Thus it will be seen, that I have provided 120

a receiving set for amateurs or others desiring the necessary apparatus already properly connected and requiring only the addition of phones and a small battery. To this end I have arranged the circuits in the manner herein set forth and added improvements whereby any material interference of the elements of the system due to their proximity and inclosure in a single cabinet, may 10 be entirely obviated, whereas, heretofore it has been necessary to dispose the elements of an undamped wave receiver set in a more or less spaced relation to gain freedom from interference with each other through induction. I have, furthermore, by my improvements, reduced the size of the elements and included them in such a small compass as to enable me to provide a receiving set in a very small portable cabinet which may, with 20 a proper aerial, readily receive undamped waves from the highest powered stations.

Having thus described my invention, what I claim as new and desire to secure by Letters Patent is:—

25 1. In a wireless receiving system, the combination of an audion detector, energized grid, filament and wing circuits, inductances in inductive relation included in said grid and wing circuits, a primary aerial inductance adjacent said inductances, condensers associated with said circuits, and a magnetic conductor movable to span any two of said inductances for interconnecting the magnetic fields thereof for tuning and other purposes substantially as described.

40 2. In a wireless receiving system, the combination of an audion detector, energized grid, filament and wing circuits, an aerial circuit, an inductance in each of said circuits, said inductances being arranged in mutual inductive relation, a magnetic conductor movable adjacent said inductances and adapted to span any two thereof, for interconnecting the magnetic field for tuning, 45 varying the frequency of oscillations and other purposes, and condensers associated with said circuits as and for the purpose set forth.

50 3. In a wireless receiving system, the combination of an audion detector, energized grid, filament and wing circuits, an aerial circuit, an inductance in each of said circuits, said inductances being short flat coils arranged in a clover-leaf arrangement, a magnetic conductor movable adjacent said inductances and adapted to span any two thereof, for interconnecting the magnetic field for tuning, varying the frequency of oscillations and for other purposes, and condensers associated with said circuits as and for the purpose set forth.

55 4. In a wireless receiving system, the combination of an audion detector, energized grid, filament and wing circuits, an aerial circuit, an inductance in each of said cir-

cuits, said inductances being arranged in mutual inductive relation, a magnetic conductor mounted for movement to span any two of said inductances and movable toward or away from the inductances thus spanned, 70 for interconnecting the magnetic field for tuning, varying the frequency of oscillations and for other purposes, and condensers associated with said circuits as and for the purpose set forth.

75

5. In a wireless receiving system for receiving undamped waves, the combination of an audion detector, energized grid, filament and wing circuits, an aerial circuit, inductances in each of said circuits, said inductances being in the nature of short flat coils, disposed in the same plane whereby mutual inductance therebetween is at a minimum, and condensers associated with the circuits, all as and for the purpose set forth.

85

6. In a cabinet receiving set, a casing including a front panel, an audion detector mounted on the front of said panel, a trio of short flat coils arranged in triangular relation, in circuit respectively with the grid and wing circuits of the detector and the aerial circuit, multipolar switches associated with each of said coils for including more or less turns of the said coils in the circuits, a rod extending between the coils and mounted for rotation and reciprocatory movement, a ring mounted on said rod whereby said ring may be moved to span any two of said coils and may be moved toward or away from the coils thus spanned, 95 an operating knob on the said rod exteriorly of the panel, a pointer movable with said rod, a scale in the path of movement of said pointer, a high tension battery for the wing circuit, a rheostat for said battery, means 100 for connecting a source of current to the filament circuit, a rheostat in said filament circuit, means for connecting a telephone receiver to the wing circuit, a plurality of condensers associated with certain of the circuits, and knobs exteriorly of the panel for adjusting said condensers.

105

7. In a wireless receiving system, the combination of an audion detector including a grid, wing and filament, inductively associated secondary coils in circuit with said grid and wing, an aerial and ground circuit, a primary coil in said aerial and ground circuit inductively associated with the aforesaid coils, a multipolar switch for each coil 115 having their contacts connected to certain windings of the coils and contact arms engageable on the contacts included in the circuits, a condenser shunted across the aerial and the ground, a magnetic conductor movable between the coils to span any two thereof and movable toward or away from the coils thus spanned, a condenser in the grid and wing circuits, variable means for energizing the wing and filament circuits,

115

120

125

130

135

and a pair of coils encompassed about the detector, one of said coils being in series with the filament and circuit, and the other coil in circuit with the grid and wing circuits whereby magnetic fields may be created about the detector to synchronize the oscillations of the wing and grid circuits.

In testimony whereof I affix my signature in the presence of two witnesses.

ERNEST C. MIGNON.
